CLAIM

The ornamental design for a golf putting practice device, as shown and described.

DESCRIPTION

FIG. 1 is a front-top perspective view of a golf putting practice device according to our new and ornamental design; FIG. 2 is a rear-bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front-top perspective view thereof, showing the golf putting practice device in an alternative configuration; and,

FIG. 10 is a rear-bottom perspective view thereof, showing the golf putting practice device in the alternative configuration.

The evenly dashed broken lines illustrate portions of the golf putting practice device that form no part of the claim. The dash-dot broken lines represent the boundaries of the claimed design and form no part of the claim. The stippling in FIGS. 1, 3, 7, and 9 represents color contrast in the sense that the areas so stippled, which may be of any color, are in color contrast with adjacent areas of the design.
